UNITED STATES PATENT OFFICE.

ALVIN L. KLECKLEY, OF CHARLOTTE, NORTH CAROLINA.

PISTON-RING REMOVER.

1,391,548.

Specification of Letters Patent. Patented Sept. 20, 1921.

Application filed August 14, 1920. Serial No. 403,559.

To all whom it may concern:

Be it known that I, ALVIN L. KLECKLEY, a citizen of the United States, residing at Charlotte, in the county of Mecklenburg 5 and State of North Carolina, have invented new and useful Improvements in Piston-Ring Removers, of which the following is a specification.

This invention relates to a device for 10 moving and replacing piston-rings and the general object of the invention is to provide a simple, economical and effective tool of this type having end portions which may be inserted between the extremities of a 15 piston-ring for the purpose of expanding the same so that it may be readily removed from the piston-ring groove and over the larger part of the piston.

A further object of the invention is to 20 provide means for retaining the ring in engaging relation with said end portions so as to prevent the ring from slipping out of the grasp of the tool.

Another object of the invention is to 25 provide a latch mechanism in connection with the movable jaws of the extractor so that the initial separation of the jaws suitable for insertion within the gap between the ends of the piston-ring may be regulated without 30 pressing the handles.

Other objects of the invention will appear as the description proceeds.

In the accompanying drawings:—

Figure 1 is a side elevation of the pre- 35 fered form of my piston-ring remover.

Fig. 2 is a side elevation showing the piston-ring remover applied to a piston-ring and the latch mechanism in engaging relation whereby the lugs are maintained in 40 slightly spaced relation.

Fig. 3 is a top view of the device.

Fig. 4 is an end view of the tool in the position shown in Fig. 2.

My device comprises principally two jaw 45 members 10 and 11 which are preferably made of flat steel plates having rounded projections 12 and 13 provided with apertures which are adapted to align when said projections are placed in overlapping relation 50 so as to receive a pivot-pin or screw 14 therethrough. The screw 14 is maintained in place by the nut 15. The jaw members 10 and 11 are formed with outwardly curved handle 16 and 17 that may be conveniently 55 grasped in the hand for the purpose of operating the jaw members about the pivot.

The opposite end, or piston-ring engaging end of the device is formed with lugs 18 and 19 integral respectively with the jaw members 10 and 11. These lugs are slightly 60 hook-shaped in order to prevent the piston-ring from slipping away from the jaws while the tool is in operation.

In order to further retain the ring in active engagement with the lugs 18, 19, side 65 plates or guides 20 and 21 are secured to opposite sides of the pivoted members 10 and 11 by means of rivets or screws 22.

The side members 20 and 21 comprise a set associated with each jaw member. The 70 plate 20 is provided with a laterally curved end 20' and the plate 21 is merely a straight strip. These plates are reversely arranged on the jaw members and the laterally curved portions 20' compensate for the overlapping 75 relation of the jaw members. These side plates project beyond the forward end of the jaw members in spaced relation, sufficient to accommodate the full width of a piston-ring 25.

Upon one of the screws 22 a latch member 26 is pivoted, said latch member having a lateral projection 27 which may be conveniently engaged by the thumb for operating the latch. The latch also is formed with 85 an inwardly projecting element 28 having a rounded part which is adapted to engage recesses 29 or 30 formed in the member 10, which engagement retains the member in one of its extreme positions, spaced approxi- 90 mately ninety degrees apart. The friction to the turning of the latch 26, however, should be sufficient to maintain it in any adjusted position between these two extremities so that the separation of the lugs 18 95 and 19 can be regulated to any desired degree.

To the right of the pivot pin 14 (shown in Figs. 1, 2) the jaw members are cut-away to form shoulders 31, 32 from which project integral stops 33, 34 in opposite directions. These stops are embraced by the ends of a coil spring 35. The studs 33, 34 thereby provide a guide and retaining means for the spring and are also of such length that they may contact and thereby 100 limit the opening movement of the jaws to prevent them from being opened wide enough to break or injure the piston-ring. When the latch is in the position shown in Fig. 1, the side plates 20, 21 act as stops 110 to limit the closing movement of the jaw members under the tension of spring 35.

It will be noted that even in the case where the jaws are completely closed as in Fig. 1, a gap 36 exists between the side members 20 and 21, which is for the purpose of giving the operator or workmen a clear view of the point of application of the tool so that they may readily see that the lugs 18 and 19 enter the gap in the piston ring and that the side plates are properly placed on the piston ring.

In order to remove a piston-ring, the piston is first removed from the engine and placed in a bench-vise by clamping the connecting rod therein just below the piston. The piston ring is then pressed into the groove so that the joint in the same will be forced out of the groove, and the lugs of the tool are then inserted in this joint or gap with the side plates 20 and 21 engaging over the upper and lower edges of the piston-ring. By pressing the handles 16 17 inwardly, against the tension of the spring 35, the lugs 18 and 19 are forced apart and consequently expand the ring so that the same may be removed from the piston.

For replacing a ring it is only necessary to expand it by placing the tool in the joint thereof as above described and force it over the large diameter of the piston until it reaches the proper groove, then the handles may be released and under tension of the spring 35 the lugs 18 and 19 will be forced together thus releasing the piston-ring and allowing it to contract within the groove and properly position itself therein.

Having described my invention, what I claim as new and desire to secure by Letters Patent, is:—

1. A piston ring remover, comprising a pair of pivoted jaw members each provided at one end with an operating handle and provided at its opposite end with a lug for insertion in the gap between the ends of a piston ring, each of said jaws having a pair of side plates secured thereto, one on each side thereof and projecting beyond the lug of said member, one of each pair of said plates adapted to engage the opposite jaw to limit the closing movement of said jaws and form a space between the outer end of said plate and the end of the complementary plate of the other jaw.

2. A piston ring remover comprising a pair of pivoted jaw members having a pair of handles at one end, lugs projecting from the other end of said members adapted to overlap in normal closed position for in-

sertion within the gap of a piston ring, a spring acting between said handles for yieldingly maintaining the jaw members in closed position, side plates secured to said jaw members and projecting beyond the same to engage opposite edges of the piston ring, said side plates also acting as stops to limit the closing movement of the jaw members under the tension of said spring.

3. A piston ring remover comprising a pair of pivoted jaw members having handles at one end, lugs projecting from the other end of said members adapted to overlap when in normal closed position for insertion in the gap of a piston ring, a spring acting between said handles for yieldingly maintaining the jaw members in closed position, side plates secured to said jaw members and projecting beyond the same to engage opposite edges of the piston ring, said side plates being spaced apart to afford an unobstructed view of the gap in the piston ring and the lugs applied therein, said plates also acting as stops to limit the closing movement of the jaw members under the tension of said spring.

4. A piston ring remover comprising a pair of pivoted jaw members, operating handles formed at one end and lugs projecting from the other end of said members for insertion within the gap of a piston ring, side plates secured to said jaw members and projecting beyond the same to engage opposite edges of the piston ring, a spring acting between said handles for yieldingly maintaining the jaw members in closed position and means for limiting the closing movement of said members according to the width of said gap.

5. A piston ring remover comprising a pair of pivoted jaw members, operating handles formed at one end and lugs projecting from the other end of said members for insertion within the gap of a piston ring, a spring acting between said handles for yieldingly maintaining the jaw members in closed position and a latch pivoted to one of said members and adapted to engage the other for varying the initial separation of said lugs according to the width of said gap.

In testimony whereof I have hereunto set my hand in presence of two subscribing witnesses.

ALVIN L. KLECKLEY.
